UNITED STATES PATENT OFFICE.

FLOYD F. FLINT, OF DETROIT, MICHIGAN, ASSIGNOR OF ONE-HALF TO MAXWELL W. BENJAMIN, OF DETROIT, MICHIGAN.

CARBURETOR.

Application filed September 14, 1923. Serial No. 662,570.

This invention relates to carburetors such as are used in connection with automobile engines and other internal combustion engines.

In the ordinary carburetors commonly used in automobiles, the mixture of air and light hydrocarbon vapor is regulated in its proportions by the adjustment of a certain valve, this being usually a needle valve, controlling the supply of fluid hydrocarbon to the carburetor. This adjustment is a manual adjustment, and when once made is usually kept in its adjusted condition since any change in the adjustment is difficult to make with accuracy and requires considerable time, even though the conditions prevailing may differ to a very considerable extent. For instance, economy in the consumption of the hydrocarbon essentially requires that the mixture will have as large a proportion of air and as small a proportion of hydrocarbon as may possibly be utilized without interfering with the effective operation of the engine.

With the manual adjustment referred to, an adjustment made for slow speed running is not economical for high speed running since the proportion of hydrocarbon for slow speed running is necessarily in excess of the proportion required for high speed running. Consequently, when running at high speed with such an adjustment, the fuel used is much more than is essential to obtain the proper results.

One important object of the present invention is to provide an improved form of carburetor wherein there will be effected an automatic adjustment of the proportions of air and fuel, this adjustment being in accordance with and compensating for the difference in conditions due to such elements in the operation of internal combustion motors, as variations in speed, variations in barometric pressure, and in fact, substantially all of the variations that occur in running engines of this type.

Again, it is very frequent in automobiles that a vacuum system is used to supply gasoline line to the carburetor. Use of such a system entails a vacuum tank located above the carburetor so that the liquid hydrocarbon may flow from such tank to the carburetor by gravity, and a more or less complicated system of pipe connections to ensure a vacuum

being maintained in such a tank. With such an arrangement any defect in the maintenance of the vacuum results in a cessation or ineffective operation of the system with the consequence that the carburetor is insufficiently supplied with the liquid fuel, and the operation of the engine either ceases or is deleteriously affected.

A second important object of the invention is to provide an improved construction of carburetor wherein the operation will be effected by a partial vacuum maintained in one portion of the carburetor structure itself, thus eliminating all special vacuum tanks and their connection.

The usual type of carburetor is provided with a fixed Venturi tube, that is to say, the relative position of the Venturi tube and the jet nozzle for the liquid hydrocarbon are fixed so that when once in position this position is maintained throughout the life of the carburetor. Efforts have been made to overcome the disadvantages resulting from a fixed Venturi tube by the employment of Venturi tubes, the position of which may be varied along the nozzle by the differences in pressure at opposite ends of the tubes, the movement being resisted by springs or the like. These efforts have been found ineffective for the purpose desired, and a third important object of the present invention is to provide a carburetor having a freely floating Venturi tube so arranged that its movement controls the richness of the explosive mixture in hydrocarbon.

Other important objects of the invention are to provide a carburetor wherein the construction is such that in the event of a breakage in the supply tank, or the line leading thereto, an auxiliary supply may be quickly adjusted; to provide an improved form of carburetor wherein sufficient explosive mixture will at all times be available to permit idling of the engine or running at slow speed through traffic, and to provide an improved form of carburetor embodying in its base a reservoir for liquid hydrocarbon and having a heat conserving jacket.

With the above and other objects in view as will be hereinafter apparent the invention consists in general of certain novel details of construction and combinations of parts here-

inafter more fully described, illustrated in the accompanying drawings and specifically claimed.

In the accompanying drawings like characters of reference indicate like parts in the several views, and:

Fig. 1 is a plan view of the complete carburetor.

Fig. 2 is a side elevation thereof.

Fig. 3 is a section on the line 3—3 of Fig. 1.

Fig. 4 is a section on the line 4—4 of Fig. 1.

Fig. 5 is a section on the line 5—5 of Fig. 2.

The present embodiment of the invention, as shown in the drawings, illustrates one preferred form thereof, but it will be understood that the principles involved may assume in actual practice, a variety of forms, and this embodiment is to be understood as merely to show one of such forms, the invention not being confined to the particular form and proportions herein illustrated.

In this embodiment there is provided a hollow bottom 10 constituting a reservoir. This bottom is of elongated form and at one end thereof there is superimposed on the bottom a float chamber 11. This float chamber 11 consists of a cylindrical tube 12 forming the side wall thereof, this tube being seated on a gasket 13 and having a top 14 closing the upper end. The tube is held on the gasket and the top on the tube by means of suitable studs 15, which extend through the top and into the top of the reservoir 10. The top of the reservoir 10 is provided, centrally of the tube 12, with an opening 16 wherein is seated a housing 17 having a valve casing 18 projecting from one side. In this valve casing is fitted a poppet valve 19 which opens from the chamber 11 inwardly to the reservoir 10 at certain times during the operation and closes communication between the float chamber and reservoir at other times. Located centrally of the housing 17 and depending from the top thereof is a valve stem guide 20, the lower end of the vertically movable valve stem 21 having fixed thereon a lower collar 22, and an upper collar 23 in spaced relation. Above the upper collar 23, the valve stem carries a valve 24 which serves to close the lower end of a suction pipe 25 screwed through the top 14. Screwed into one side of the top is a pipe T 26 having its upper end closed normally by a plug 27. To this pipe T is connected a casing 28 containing an upwardly opening check valve 29 in its upper portion, and a strainer 30 in its lower portion. The lower portion of the casing 28 is closed by a pipe connection 31 to which is connected the gasoline supply pipe 32 leading from the usual gasoline tank (not shown). At 33 is the float, and leading from the top 14 downwardly through this float and opening into the housing 17 is a vent tube 34, the vent tube having a slight clearance at the top, as shown at 35. In other words, the vent

tube does not fit tightly in the top 14, but permits air to enter around it. Extending upward from the upper end of the housing is a carbureting chamber 36, surrounded on its side by a jacket 37 and having at its top a flange 38 for connection to the intake manifold of the engine. The lower end of the carbureting chamber 36 is reduced slightly in diameter to provide a shoulder so as to limit the downward movement of a Venturi tube 39 mounted to slide freely in the carbureting chamber between said shoulder and a stop ring 40 fixed at the proper point above the Venturi tube. Extending upward into the carbureting chamber through the top of the reservoir 10 is a jet tube or nozzle 41 which terminates close to the bottom of the chamber 10. The pipe 25 is connected to the upper part of the chamber 36 by means of a pipe connection 42 opening into said chamber 36 above the usual butterfly valve 43.

Extending up from the top of the reservoir 10 between the chamber 36 and tube 12 is a tubular housing 44 through which passes a second jet tube 45 opening into a lateral passage 46 communicating with the interior of the chamber 36 by a short tube 47 which passes through the jacket space 37. The outer end of this chamber 46 is closed by a plug 48. It will be observed that the jet tube 45 is free from the sides of the tube 44 so that the latter not only houses the jet tube 45, but acts as a vent for the chamber 10. The pipe connection 42 is provided, at the end adjacent the chamber 36, with a member 49 having a valve seat 50 at its inner end, and in the flange 38 is a valve chamber 51, a floating check valve 52 being located in said chamber and serving to seat on the valve 50 during certain periods of the operation of the device so as to prevent any back pressure from the chamber 36 passing through the pipe connection 42. At the lower part of the chamber 36 there are provided certain air ports 53, which are formed by tubes passing through the jacket space 37 and opening outwardly under a rotating sleeve 54 having corresponding openings 55 formed therein, the sleeve being shiftable circumferentially around the chamber 36 so as to control the admission of air to the lower part of said chamber.

In the operation of the device, let it be supposed that the carburetor has been connected up to the gasoline tank and the intake manifold, and that no gasoline is in the carburetor. In starting, the operator steps on his starter which of course results in turning the engine over. This produces a suction in the upper part of the chamber 36, the butterfly valve being closed. Consequently, a partial vacuum is produced in the chamber 11, and this starts the gasoline from the tank through the pipe 32, past the valve 29 and through the pipe connection 26, from whence it passes into the chamber 11. It is to be un-

derstood that the clearance at 35 is of such slight degree, that the incoming air at this point does not interfere with sufficient vacuum being produced to cause the gasoline to pass from the tank in the manner described. As the gasoline rises in the chamber 11, the head produced opens the valve 19 and it flows past this valve into the reservoir 10. After filling the reservoir it rises in the housing tube 44, and at the same time the float 33 rises until it engages the upper collar 23 whereupon it lifts the valve 24 and closes the lower end of the pipe connection 25 cutting off the vacuum. The valve 24 then remains closed until the gasoline drops in the chamber 11 sufficiently to bring the float 33 into contact with the lower collar 22 whereupon the weight of the float and the valve 24 and its stem collars will act to again open the pipe connection 25 and the operation is again repeated. Now so long as the butterfly valve 43 remains closed, gasoline will flow up through the jet pipe 45 under the influence of the suction strokes of the engine, and will pass into the upper part of the chamber 36 above the butterfly valve. In order to provide for sufficient air to make an explosive mixture with this gasoline, a vent 56 opens into the chamber 46, and is controlled by an ordinary needle valve 57. Under these conditions, the explosive mixture will be reached in hydrocarbon and the engine will start, and so long as the butterfly valve is closed, will idle or run slowly.

It is a well known fact that whenever an engine is stopped after running and the crank shaft rocks back and forth to a certain degree, this causes a certain amount of back pressure at the time when the inlet valves are open. This back pressure, if not prevented from reaching the chamber 11 would cause pressure in that chamber with the consequence that the gasoline would be ejected through the pipe 34, and in order to prevent this, the valve 52 is provided. The action of this valve is that whenever this back pressure takes place in the manner described, the valve 52 promptly closes and thus no pressure is exerted in the chamber 11 or the reservoir 10.

When it is desired to increase the speed of the engine the butterfly valve is opened in the manner common to ordinary carburetors. Upon the opening of this valve, the suction in the chamber 36 draws gasoline through the jet tube 41. Now, dependent on the speed at which the engine is running, the Venturi tube will assume a position between the shoulder in the lower part of the chamber 36 and the ring 40. This movement of the Venturi tube automatically maintains the proper ratio between the fuel vapor and air at all stop speeds. This ratio is maintained without any alteration in the setting of either the sleeve 54 or the butterfly valve 43. In

order to understand this, an example may be given. Suppose the automobile carrying this carburetor is running along level ground. Also suppose the speed to be in the neighborhood of forty miles per hour. Now the Venturi tube 39 under these conditions will have risen until the proper proportion of air and fuel vapor is obtained. Upon the automobile reaching a hill, the conditions due to hill climbing will cause a slowing down of the speed, and by reason of this drop in the speed, the Venturi tube 39 will tend to fall toward the bottom of the chamber 36. This downward movement of the Venturi tube results in increasing the velocity of air at the tip or nozzle of the jet tube 41, and consequently increases the proportion of gasoline mixed with the air, thus enriching the mixture so that additional power is given in climbing the hill. When the top of the hill has been reached, the engine naturally speeds up and the Venturi tube rises, thus decreasing the velocity of air past the top of the gasoline jet tube 41 and causing the mixture to become leaner.

It is of course obvious that the richness of the mixture may be controlled by closing or partially closing the ports 53 by movement of the sleeve 54. For instance, in starting the engine in cool weather, it is sometimes advisable to close or partially close these ports until the engine is heated up whereupon the sleeve may be restored to its running position. Now this sleeve is provided on one side with a lug 58 which is suitably connected by a reach rod (not shown) to a handle or the like on the dash of the machine. Similarly the butterfly valve is likewise provided with means for operation from the dash, the valve having a stem 59 carrying a lever 60 adapted to be connected by a rod with a suitable operating handle on the dash. The jacket 37 is provided with an inlet connection 61 which communicates by suitable pipe connection including a shut-off with the exhaust, this pipe connection, and the shut-off not being deemed necessary here to be shown, as they are of ordinary construction. Also the jacket is provided with an outlet connection 62. Plugs 63 are provided in the bottom of the reservoir 10 to permit access to the jet tubes 41 and 45 for change or renewal of these parts and the bottom of the reservoir is also provided with a drain cock 64 of ordinary type in order that the gasoline may be drained therefrom when desired. This drain cock also affords means for definitely ascertaining whether the carburetor contains gasoline.

It will be observed that the shut-off to the jacket connection is for the purpose of regulating the temperature of the instrument, it being obvious that the greater the quantity of the hot exhaust gases which are allowed to pass through the jacket, the hotter the chamber.

ber 36 becomes, and that the opposite is true. It will be further noted that it is the intent of the invention to have the jacket 37 of such size that not only will the heat from this jacket provide heat for the chamber 36 but it will also be sufficient to heat the gasoline in the reservoir 10 and thus heat the entire instrument, thus enabling the more effective vaporization of the gasoline. Furthermore, the construction is such that the air entering the lower part of the chamber 36 is warm while the gasoline passing through the jet tube 41 is hot. The mixture which takes place at the mouth of the Venturi and jet tubes then cools off to a certain extent, and entering the engine is of course heated by the heat of the engine itself and the action of compression thus refining the mixture and causing a better combustion.

Reference has been made to a plug 27 in the top of the pipe connection 26. With this instrument in the event of any cessation of flow through the pipe 32 such as may be caused by the rupture of the gasoline supply tank, or the breaking of this pipe, or the clogging of the same does not necessarily stop the operation of the carburetor, because the plug 27 may be removed and the ordinary tube, such as a rubber pipe may be connected to the pipe fitting 26 at this point, and its other end may be connected to any suitable source of supply, such as a can of gasoline, or a bucket of gasoline, or any other container whereupon the instrument will operate precisely in the same manner as before. Furthermore, if the vacuum system herein contained should for any cause fail, connection may be made through the pipe connection 26 as before and gravity feed used. For instance, the rubber pipe referred to might be used to siphon the gasoline from a bucket to the chamber 11. Thus with the three methods of providing gasoline feed to the chamber 11, the continued operation of the vehicle is assured so long as gasoline can be obtained to feed the chamber 11.

There has thus been provided a highly efficient device of the kind described and for the purpose specified.

It is obvious that minor changes may be made in the form and construction of the invention without in any way departing from the material spirit thereof. It is not, therefore, desired to confine the invention to the exact form herein shown and described, but it is wished to include all such as properly come within the scope claimed.

Having thus described the invention, what is claimed as new, is:

1. In a carburetor, a reservoir forming a base, a float chamber on top of said reservoir having a minute orifice in the top affording constant communication with the outer air, the capacity of the reservoir being substantially greater than the normal fuel content of the float chamber, said float chamber having valve controlled communication with the reservoir, said reservoir having free communication with the atmospheric air above the level at which the fuel stands in the float chamber, and a mixing chamber supported on the other end of the reservoir and having communication therewith.

2. In a carburetor, a reservoir forming a base, a float chamber on top of said reservoir having a minute orifice in the top affording constant communication with the outer air, the capacity of the reservoir being substantially greater than the normal fuel content of the float chamber, said float chamber having valve controlled communication with the reservoir, said reservoir having free communication with the atmospheric air above the level at which the fuel stands in the float chamber, a mixing chamber supported on the other end of the reservoir and having communication therewith, and pipe communication between the upper end of the mixing chamber and the top of the float chamber whereby the valve communication is held closed under predetermined conditions of fuel level in the float chamber.

3. In a carburetor, a fuel reservoir forming a base and having sufficient capacity to permit operation of the carburetor for a considerable time without additional fuel entering the reservoir, a float chamber on one end of the reservoir and having communication therewith, a check valve controlling the flow of fuel to said reservoir and opening toward the reservoir, a mixing chamber at the other end of the reservoir and communicating therewith, a pipe communication between the top of the float chamber and the mixing chamber and arranged to produce pressure effects in the float chamber whereby to control opening and closing of said check valve, said reservoir having free communication with the atmospheric air at a point above the level at which the fuel stands in the float chamber.

In testimony whereof I affix my signature.

FLOYD F. FLINT.
